UNITED STATES PATENT OFFICE

2,512,602

CONTAINER

John G. Bell, Chicago, Ill., assignor, by means of assignments, to Morris Paper Mills, Chicago, Ill., a corporation of Illinois

Application February 19, 1947, Serial No. 729,505

13 Claims. (Cl. 229—5.5)

1

This invention relates to a new and improved container and more particularly a collapsible container formed of flexible sheet material which may be shipped and stored flat in knocked down condition.

This container may be made of cardboard or other relatively light weight material and is particularly suited for packaging ice cream or other food products. Inasmuch as these containers are discarded after one use, it is highly desirable that they be of economical construction.

It is therefore an object of the present invention to provide a container which may be quickly assembled at the place where it is to be filled.

It is another object to provide a container which may be shipped and stored in knocked down or flat condition and which may be assembled without the use of adhesives.

It is a further object to provide a container which may be made from light weight material and which may be manufactured at a low cost.

It is another object to provide a container which may be easily assembled without powered machinery.

Another object is to provide a multi-walled container having insulating characteristics.

A further object is to provide a multi-walled container constructed of light weight material which has adequate rigidity and provides extra protection to the contents in that damage to the outer wall will not necessarily affect the inner wall.

Another object is to provide a container in which the top and bottom closures cooperate with the lateral walls to maintain the shape of the container and strengthen the walls.

With these and other objects in view, the invention consists of certain novel features of construction as will be more fully described and particularly pointed out in the specification, drawings and claims appended hereto.

In the drawings which illustrate an embodiment of the invention and wherein like reference characters are used to designate like parts:

Figure 1 is a plan view on a reduced scale of a blank for forming the side walls of the container.

Figure 2 is a vertical elevation of the container with its top closure separate therefrom.

Figure 3 is a fragmentary sectional view of the container and closure.

Figure 4 is a fragmentary transverse section taken on the line 4—4 of Figure 3.

Figure 5 is a top plan view of the container closure shown in Figure 2.

Referring to the drawing, the side walls of the

2

container are made from the blank 12 shown in Figure 1. The length of the blank is more than twice the circumference of the assembled container. The upper margin of the blank is folded over outwardly to form the rolled edge 14. The lower margin is folded over inwardly to form the rolled edge 16, indicated by the broken lines in Figure 1. The width of the blank after the margins are folded is the height of the side walls of the assembled container. The right half of the blank forms the inner wall and the left the outer wall. The outer or left end of the blank has tabs 18 adapted to be inserted in the vertically aligned slots 20 which are at approximately the center of the blank.

The broken lines 22 indicate creases in the blank which make it possible to easily fold it into a compact flat rectangular shape for purposes of storage and transportation. The tabs 18 may be inserted in the slots 20 after the outer wall has been wrapped around the inner and the blank may then be folded for storage, thus facilitating ultimate assembly of the container. The slots 20 are in the outer wall of the container eliminating the possibility of the contents leaking through them. In place of these tabs the outer end may be cemented or otherwise secured without the cement coming in contact with the contents of the container and this may be done either at the time of fabrication or assembly. An adhesive may be applied to the blank at the time of fabrication which would merely require that the adhesive be moistened and the outer end secured at the time of assembly; this latter operation may be performed while the blank is in folded condition.

The container is closed at the bottom by a disk 24 shown in Figure 3. This disk may be made of cardboard or other material which may be of a heavier weight than the side walls. After the outer end of the blank 12 has been secured as by inserting the tabs 18 in the slots 20, the disk 24 may be inserted by pushing it downwardly until the edge of the under surface is seated on the inner rolled edge 16. The edge of the disk holds the walls outwardly in a cylindrical shape as distinguished from the collapsed and folded condition prior to the insertion of the disk. The rolled edge 16 may be previously glued or otherwise secured to the walls of the container to insure adequate support for the disk 24. The glued portion being below the disk it does not come in contact with the contents of the container.

The top closure consists of a disk 26 which is seated on the rolled edges 14 of the inner and

outer walls and a rim member which consists of a downwardly extending flange 28 which engages the outer rolled edge 14, and a portion 30 projecting above the disk 26 folded back upon itself and terminating in horizontally projecting tabs 32 which engage the upper surface of the disk 26. The rim member may be made from a strip of material of the same type as the side walls. The tabs 32 are formed by notching a margin of the strip and the folding lines are scored. The strip has extended ends 34 which are overlapped and suitably secured together by glue or otherwise fastened forming a ring. The rim may be doubled and flattened for storage purposes and the folds may be made at the time of assembly when the rim is opened up and the tabs 32 turned inwardly and downwardly forming the projecting portion 30 and then inwardly and horizontally along the second scored line so that the tabs are in a position to overlay the disk 26. To install the cover the disk may be seated on the rolled edges 14 and the rim placed over it or the disk may be inserted in the rim and the rim with the disk then placed on the container with the flanges 28 engaging the rolled edge 14.

The upper rolled edges 14 strengthen the upper margin of the container and have a stiffening effect. There being a rolled edge on the inside as well as the outside wall, a seat is provided for the disk 26 which is four times the thickness of the side wall material. The flange 28 of the cover member has a relatively close fit with the outer rolled edge 14 which tends to push the flange outwardly, particularly when the container is filled, this in turn tends to urge the tabs 32 downwardly against the upper surface of the disk 26 to maintain it in place.

The inner rolled edge 14 tends to maintain the inner and outer walls of the container in spaced relation. Similarly, the lower rolled edge 16 of the outer wall has the same effect, which results in a certain amount of air space between the walls of the container with its attendant insulating properties. This also gives additional protection to the contents of the container in that damage to the outer wall is less likely to penetrate the inner wall.

It is to be understood that this application is not to be limited by the exact embodiment shown, which is merely by way of illustration and not limitation as various and other forms of the device will, of course, be apparent to those skilled in the art without departing from the spirit of the invention or the scope of the claims.

I claim:

1. A container having a top and bottom and lateral walls, the lateral walls comprising a continuous strip of material having the upper edge rolled outwardly and downwardly and the lower edge rolled inwardly and upwardly, said strip being of such a length that when wrapped upon itself an inner and outer wall is formed, the upper rolled edge of the inner wall and the lower rolled edge of the outer wall being positioned between said walls and serving to space apart said inner and outer walls, said bottom comprising a disk adapted to seat upon the lower rolled edge of the inner wall, said top comprising a disk adapted to seat upon the upper rolled edges of the inner and outer walls and a rim adapted to engage the rolled edge of the outer wall, the upper portion of said rim projecting above said disk and being folded upon itself and having in-

wardly projecting tabs for engaging the outer surface of said disk.

2. A container having a top and bottom and lateral walls, the lateral walls comprising spaced apart inner and outer walls, the upper edges thereof being rolled outwardly and downwardly, the rolled edge of the inner wall being between the inner and outer walls so as to space said walls apart adjacent the upper edges thereof, the lower edges of said walls being rolled upwardly and inwardly, the rolled edge of the outer wall being between the outer and inner walls so as to space said walls apart adjacent the bottom edges thereof.

15. 3. A container having a top and bottom and lateral walls, the lateral walls comprising a continuous strip of material wrapped upon itself to form spaced apart inner and outer walls, the upper edges of the walls being rolled outwardly and downwardly, the rolled edge of the inner wall being between the inner and outer walls so as to space said walls apart adjacent the upper edges thereof, the lower edges being rolled inwardly and upwardly, the lower rolled edge of the outer wall being between the outer and inner walls so as to space said walls apart adjacent the bottom edges thereof, said bottom comprising a disk adapted to be seated upon the lower rolled edge of the inner wall.

20. 4. A container having a top and bottom and lateral walls, the lateral walls comprising a continuous strip of material wrapped upon itself to form spaced apart inner and outer walls, the upper edges of the walls being rolled outwardly and downwardly, the rolled edge of the inner wall being between the inner and outer walls so as to space said walls apart adjacent the upper edges thereof, the lower edges being rolled inwardly and upwardly, the lower rolled edge of the outer wall being between the outer and inner walls so as to space said walls apart adjacent the bottom edges thereof, said top including a disk adapted to be seated upon said upper rolled edges.

25. 5. A container having a top and bottom and lateral walls, the lateral walls comprising a continuous strip of material wrapped upon itself to form spaced apart inner and outer walls, the upper edges of the walls being rolled outwardly and downwardly, the rolled edge of the inner wall being between the inner and outer walls so as to space said walls apart adjacent the upper edges thereof, the lower edges being rolled inwardly and upwardly, the lower rolled edge of the outer wall being between the outer and inner walls so as to space said walls apart adjacent the bottom edges thereof, said top including a disk adapted to be seated upon said upper rolled edges and a rim adapted to engage the upper rolled edge of the outer wall having portions overlaying said disk.

30. 6. A container having a top and bottom and lateral walls, the lateral walls comprising a continuous strip of material wrapped upon itself to form spaced apart inner and outer walls, the upper edges of the walls being rolled outwardly and downwardly, the rolled edge of the inner wall being between the inner and outer walls so as to space said walls apart adjacent the upper edges thereof, the lower edges being rolled inwardly and upwardly, the lower rolled edge of the outer wall being between the outer and inner walls so as to space said walls apart adjacent the bottom edges thereof, said bottom comprising a disk adapted to be seated upon the lower rolled edge of the inner

wall, said top including a disk adapted to be seated upon said upper rolled edges.

7. A container having a top and bottom and lateral walls, the lateral walls comprising a continuous strip of material wrapped upon itself to form spaced apart inner and outer walls, the upper edges of the walls being rolled outwardly and downwardly, the rolled edge of the inner wall being between the inner and outer walls so as to space said walls apart adjacent the upper edges thereof, the lower edges being rolled inwardly and upwardly, the lower rolled edge of the outer wall being between the outer and inner walls so as to space said walls apart adjacent the bottom edges thereof, said bottom comprising a disk adapted to be seated upon the lower rolled edge of the inner wall, said top comprising a disk adapted to be seated upon said upper rolled edges, and a rim adapted to engage the upper rolled edge of the outer wall having portions overlaying said disk.

8. A container having a top and bottom and lateral walls, the lateral walls comprising spaced apart inner and outer walls, the upper edges thereof being rolled outwardly and downwardly, the rolled edge of the inner wall being between the inner and outer walls so as to space said walls apart adjacent the upper edges thereof, the lower edges of said walls being rolled upwardly and inwardly, the rolled edge of the outer wall being between the outer and inner walls so as to space said walls apart adjacent to bottom edges thereof, said top comprising a disk adapted to be seated upon the upper rolled edges, and a rim having a downwardly extending flange for engaging the upper rolled edge of the outer wall, the upper portion of said flange projecting above said disk and having laterally extending tabs for engaging the outer surface of said disk.

9. A container having a top and bottom and lateral walls, the lateral walls comprising spaced apart inner and outer walls, the upper edges thereof being rolled outwardly and downwardly, the rolled edge of the inner wall being between the inner and outer walls so as to space said walls apart adjacent the upper edges thereof, the lower edges of said walls being rolled upwardly and inwardly, the rolled edge of the outer wall being between the outer and inner walls so as to space said walls apart adjacent the bottom edges thereof, said bottom including means adapted to be seated upon the lower rolled edge of the inner wall.

10. A container having a top and bottom and lateral walls, the lateral walls comprising spaced apart inner and outer walls, the upper edges thereof being rolled outwardly and downwardly, the rolled edge of the inner wall being between the inner and outer walls so as to space said walls apart adjacent the upper edges thereof, the lower edges of said walls being rolled upwardly and inwardly, the rolled edge of the outer wall being between the outer and inner walls so as to space

said walls apart adjacent the bottom edges thereof, said top including means adapted to engage the upper rolled edge of the outer wall.

11. A container having a top and bottom and lateral walls, the lateral walls comprising spaced apart inner and outer walls, the upper edges thereof being rolled outwardly and downwardly, the rolled edge of the inner wall being between the inner and outer walls so as to space said walls apart adjacent the upper edges thereof, the lower edges of said walls being rolled upwardly and inwardly, the rolled edge of the outer wall being between the outer and inner walls so as to space said walls apart adjacent the bottom edges thereof, said top including means adapted to be seated upon the upper rolled edges and to engage the outer surface of the upper rolled edge of the outer wall.

12. A blank adapted to be formed into the continuous lateral wall of a container of the class described, comprising, an elongated rectangular strip of flexible material having a length equal to approximately twice the periphery of said continuous lateral wall, one of the lateral edges of said strip being rolled over upon itself with the other lateral edge being rolled over upon itself on the opposite side from said first rolled edge, said strip upon being wrapped around itself with the free ends secured to the adjacent wall so as to form spaced inner and outer walls, said inner and outer walls being spaced apart at one end by the outwardly rolled edge of the inner wall and being spaced apart at the opposite end by the inwardly rolled edge of the outer wall.

13. The blank called for in claim 12 wherein one end of said strip is provided with at least one retention tab and wherein a transverse slot is provided for each of said tabs, said slots being located approximately midway between the ends of said strip and disposed so as to receive the respective retention tabs when said blank is formed into said container wall.
